TONGUE PROTECTOR DEVICE

Reuben J. Gunderson, Chicago, Ill., assignor to
Animal Tongue Protector, Inc., Chicago, Ill.,
a corporation of Illinois

Application February 7, 1938, Serial No. 189,085

16 Claims. (Cl. 17—1)

The present invention relates generally to tongue protector devices. More particularly the invention relates to that type of device which serves to protect the tongue of a hog carcass against mutilation or puncture by the teeth during machine dehairing of the carcass and comprises a tongue holding or retaining member and a plurality of rearwardly divergent tooth-equipped spring metal arms which are connected 5 at their front ends to the member and are adapted to be contracted or brought together during insertion of the device into the mouth of the carcass and upon release thereof spring outwards in such manner as to engage the adjacent 10 portions of the mouth of the hog and hold the member in its operative tongue holding or retaining position.

One object of the invention is to provide a tongue protector device of this type which effectively and efficiently fulfills its intended purpose and is an improvement upon, and has certain advantages over, that which is shown in and forms the subject matter of an application for United States Letters Patent, filed by me February 23, 1937, Serial No. 127,059.

Another object of the invention is to provide a tongue protector device of the type under consideration in which the tongue holding and retaining member is formed of strong flexible material, such as canvas, and is so attached to the spring metal arms that when the device is in its operative position it surrounds or encases the front end of the tongue and prevents the latter from swinging sidewise into engagement with the 35 teeth of the carcass.

A further object of the invention is to provide a tongue protector device of the type and character under consideration in which the spring metal arms are four in number and are arranged 40 and connected together in such manner that when the device is in its operative position one arm operates to engage the roof of the mouth of the carcass, two arms operate to engage the sides of the mouth and the fourth operates to engage the front portion of the lower jaw at a point adjacent to the tip of the tongue.

A still further object of the invention is to provide a hog carcass tongue protector device which is generally of new and improved construction and may be manufactured at a low and reasonable cost as well as applied and removed with facility.

Other objects of the invention and the various advantages and characteristics of the present protector device will be apparent from a con-

sideration of the following detailed description.

The invention consists in the several novel features which are hereinafter set forth and are more particularly defined by claims at the conclusion hereof.

In the drawing which accompanies and forms a part of this specification or disclosure and in which like numerals of reference denote corresponding parts throughout the several views:

Figure 1 is a perspective of a tongue protector 10 device embodying the invention;

Figure 2 is a fragmentary vertical longitudinal sectional view of the device, illustrating in detail the manner in which the canvas tongue holding or retaining member is connected to the rearwardly divergent spring metal arms;

Figure 3 is a vertical longitudinal sectional view showing the device in its operative position within the mouth of a hog carcass and illustrating the manner in which two of the spring metal arms serve as a result of inward bending thereof during manipulation of the device into its operative position, to grip yieldingly or resiliently the interior of the mouth of the carcass and thus hold the tongue holding member in place.

Figure 4 is a horizontal longitudinal sectional view showing the device in its operative position and illustrating the manner in which the other two spring metal arms are adapted to engage the sides of the mouth of the carcass and coact with the two arms shown in Figure 3 to hold the cloth member in enveloping relation with the front or tip end of the carcass tongue.

Figures 5 and 6 are top and bottom perspective views, respectively, of the clip for holding the spring metal arms against sidewise displacement with respect to one another;

Figure 7 is a detail sectional view on the line 7—7 of Figure 1; and

Figure 8 is a plan view of the cloth tongue holding or retaining member prior to attachment 40 to the spring metal arms.

The device which is shown in the drawing constitutes the preferred embodiment of the invention. It is adapted to hold in place and prevent mutilation, puncture or teeth slashing of the tongue T of a hog carcass C during machine dehairing of the carcass and comprises a tongue holding or retaining member 9 and four arms 10, 11, 12 and 13 for holding the member 9 in its 45 operative position as hereinafter described.

The tongue holding or retaining member 9 is formed of flexible material such as canvas, and is shaped to form a pocket for the front end of the tongue of the carcass. It is adapted to be 50 55

washed and sterilized after each use of the device and is so shaped and designed that it embodies a rounded tip portion 14, a top portion 15, a pair of side portions 16 and a bottom portion 17. The top portion 15 extends rearwardly from the tip portion 14 and is adapted when the protector is in its operative position, as shown in Figure 3, to overlie the front portion of the tongue and protect the top portion of the tongue 10 from engaging the teeth in the upper jaw of the carcass C. The side portions 16 extend rearwardly from the tip portion 14 and are adapted to lap or straddle the sides of the front end of the tongue T, as shown in Figure 4. The bottom 15 portion 17 extends downwardly and is adapted when the device is in its operative position to extend rearwardly as well as downwardly and to underlie the tip of the tongue, as shown in Figure 3. The top and side portions 15 and 16 are 20 pointed at their rear extremities. The tongue holding and retaining member 9 is formed from a blank like that shown in Figure 8 of the drawing. Said blank is cut with a V-shaped notch 17a and the part thereof which is adapted to form the bottom portion 17, and is formed into the member by stitching together or otherwise securing in lapped relation the longitudinal portions of the blank which define the sides of the notch. When such portions are stitched or otherwise 30 secured in place the member is of the desired shape and has the tip portion 14 at the inner end of the notch. The side portions 16 of the member 9 are sufficiently loose so that folds are formed therein when the device is inserted into 35 its operative position in the mouth of the hog carcass C. The edges of the cloth member 9 are doubled back and stitched to form a marginal hem 18 around the member.

The arms 10, 11, 12 and 13 are formed of spring 40 metal and are externally disposed with respect to the member 9. The arms 10 and 11 are formed from a single bowed or U-shaped strip and are arranged so that their juncture point, that is, the bow or bend of the strip, overlies the tip portion 14 of the cloth tongue holding or retaining member 9. The arm 10 overlies the top portion 15 of the member and extends from the tip portion 14 to the point at the extremity of said top portion 15. It is adapted when the device is 45 in its operative position to press upwardly against the roof of the mouth of the hog carcass and has at its outer or rear end an upstanding tooth 19 which either penetrates or embeds itself in the roof of the mouth of the carcass and thus secures the arm 10 in place. The rear end of the arm 10 is connected to the pointed extremity of the top portion 15 of the member 9 by way of a rivet 20 which, as shown in Figure 1, is located immediately adjacent to the tooth 19 and causes 50 the top portion of the member 9 to move in harmony with the spring metal arm 10. The arm 11 is materially shorter than the arm 10. It extends downwardly from the tip portion 14 of the member 9 to the extremity of the central part of the bottom portion 17 of said member and is connected to said extremity by way of a rivet 21. The lower end of arm 11 is provided with an outwardly extending tooth 22, which as shown in Figure 3, is adapted when the protector device is in its 55 operative position to extend downwardly and embed itself into the front portion of the lower jaw. The bow or U-shaped bend between the arms 10 and 11 is connected to the tip portion 14 of the member 9 by way of a rivet 23. The arms 12 and 70 13 are formed from a single U-shaped strip and

extend at substantially right angles to the arms 10 and 11. They extend from the tip portion 14 of the member 9 to the pointed extremities of the side portions 16 of said member and are connected to such extremities by way of rivets 24. 5 The outer rear ends of the arms are provided with out-turned teeth 25 which are adapted to engage the sides or cheeks of the mouth of the carcass in such manner that the arms 12 and 13 contact with the arms 10 and 11 to hold the member 9 in place around the front end of the tongue T of the carcass. The bow or bend of the strip from which the arms 12 and 13 are formed overlies and crosses the bow or bend of the strip from which the arms 10 and 11 are formed adjacent to the tip portion 14 of the member 9 and is secured to such tip portion by way of the rivet 23. Before insertion of the device into the mouth of the carcass C the arms 10, 11, 12 and 13 are adapted to be contracted or pressed together in the barrel of 20 a gun-type tool like that which is shown in my aforesaid patent application Serial No. 127,059. After proper contraction of the arms the device is inserted into the mouth of the carcass in such manner as to bring the front end of the tongue 25 T into the pocket which is formed within and defined by the tongue holding or retaining member 9. Thereafter the arms are released by proper manipulation of the tool, and, as the result of their inherent resiliency, spring outwards into 30 their operative position. When the device is properly positioned within the mouth of the carcass the arm 10 fits against and is secured by its tooth 19 to the roof of the mouth, the arms 12 and 13 press against the sides of the mouth or 35 cheeks of the carcass and are secured or anchored in place by the teeth 25 at their outer extremities and the arm 11 extends downwardly and rearwardly and presses against and is connected by its tooth 22 to the front part of the lower jaw 40 of the carcass. As the result of the spring of the arms and the action of the teeth, member 9 is securely held in place and can not become loose as the result of the blows which are imparted to the carcass during machine dehairing of the latter. After the machine dehairing operation the 45 device is removed by suitably springing inwards the arms 10, 11, 12 and 13. After use the device is washed and sterilized in any suitable manner so that it is fit for reuse. 50

In order to prevent sidewise pivotal movement of the arms 12 and 13 with respect to the arms 10 and 11 a square clip 26 is provided. This clip is in the form of a sheet metal stamping and is disposed between the inner ends of the arms 10 and 11 and the inner ends of the arms 12 and 13, 55 that is, between the bows or bends of the two metallic strips which form the arms of the device. It is mounted on the shank of the rivet 23 and is provided with a pair of upwardly and inwardly extending oppositely facing flanges 27 and a pair of downwardly and inwardly extending oppositely facing flanges 28. The flanges 27 are integral with the two opposed side margins of the clip and extend around and grip the side edges of the bow or bend of the U-shaped strip forming the arms 12 and 13 (see Figure 1). The downwardly and inwardly extending flanges 28 are formed integrally with the other two opposed side margins of the clip 26 and extend around and grip the side edges of the U-shaped strip forming the arms 10 and 11. As the result of the gripping action of the two pairs of flanges 27 and 28 the four arms of the device are effectively held against sidewise displacement with respect to one another. 70 75

The herein described tongue protector device consists of but a small number of parts and hence may be manufactured at a low and reasonable cost. It is efficient in operation due to the fact that the cloth tongue holding or retaining member 9 is held in place by four tooth-equipped spring metal mouth engaging arms. In addition the construction is such that it may be applied to and removed from the mouth of the carcass with facility and is not likely to damage any of the important meaty portions of the carcass mouth.

The invention is not to be understood as restricted to the details set forth, since these may be modified within the scope of the appended claims, without departing from the spirit and scope of the invention.

Having thus described the invention, what I claim as new and desire to secure by Letters Patent is:

1. A device for protecting the tongue of a carcass against mutilation during machine dehairing of the carcass, comprising a cup-shaped member adapted to envelop the front end of the tongue and formed of such flexible material that it is readily collapsible, and means associated with the member and adapted to engage certain of the fleshy portions of the interior of the mouth of the carcass and hold said member in substantially fixed position within the carcass mouth.

2. A device for protecting the tongue of a carcass against mutilation during machine dehairing of the carcass, comprising a cloth cup-shaped member adapted to be sleeved over the front end of the tongue into enveloping relation therewith, and means connected to the member and adapted to engage the interior of the mouth of the carcass and hold said member in a substantially fixed position within the carcass mouth.

3. A device for protecting the tongue of a carcass against mutilation during machine dehairing of the carcass, comprising a cup-shaped member adapted to be sleeved over the tongue into enveloping relation with the latter and formed of such material that it is readily collapsible, and means for holding said member in its operative position, including a tooth-equipped spring arm connected to, and disposed entirely exteriorly of, the member and adapted to spring against and have its tooth embed itself in a portion of the fleshy part of the mouth of the carcass.

4. A device for protecting the tongue of a carcass against mutilation, comprising a cup-shaped member adapted to be sleeved over the tongue into enveloping relation with the latter and formed of such flexible material that it is readily collapsible, and means for holding said member in a substantially fixed position within the carcass mouth, including a spring arm disposed entirely exteriorly of the member and having one end thereof connected to the tip portion of the member and its other end adapted to spring against and engage yieldingly a portion of the fleshy part of the mouth of the carcass.

5. A device for protecting the tongue of a carcass against mutilation, comprising a cup-shaped member adapted to be sleeved over the tongue into enveloping relation with the latter, and means for holding said member in a substantially fixed position within the carcass mouth, including a spring arm having one end thereof riveted to the tip portion of the member and its other end provided with a tooth and adapted to spring against and engage yieldingly, and to have its

tooth embed itself in, a portion of the mouth interior.

6. A device for protecting the tongue of a carcass against mutilation during machine dehairing of the carcass, comprising a member adapted to engage the tongue and hold it in the lower jaw, and means for holding said member in its operative position, including a downwardly extending tooth equipped spring arm adapted to engage and press against, and have its tooth embed itself in, the portion of the lower jaw that is directly beneath the tip of the tongue.

7. A device for protecting the tongue of a carcass against mutilation, comprising a flexible member adapted to engage the tongue and hold it in the lower jaw, and means for holding said member in its operative position, including a downwardly extending spring arm having the upper end thereof connected to said member and its lower end provided with a tooth and adapted to engage yieldingly, and have its tooth embed itself in, the front portion of said lower jaw of the carcass.

8. A device for protecting the tongue of a carcass against mutilation, comprising a cup-shaped member for enveloping the tongue, and means for holding said member in a substantially fixed position within the carcass mouth, including a downwardly extending spring arm having the upper end thereof connected to the tip portion of said member and its lower end adapted to engage and press against the front portion of the lower jaw of the carcass.

9. A device for protecting the tongue of a carcass against mutilation, comprising a flexible cup-shaped member for enveloping the tongue, and means for holding said member in a substantially fixed position within the mouth of the carcass, including a downwardly extending spring arm having the upper end thereof riveted to the tip portion of said member and its lower end provided with a tooth and adapted to engage yieldingly, and have its tooth embed itself in, the front portion of the lower jaw of the carcass.

10. A device for protecting the tongue of a carcass against mutilation, comprising a cup-shaped member adapted to envelop the tongue and formed of such flexible material that it is readily collapsible, and means for holding said member in a substantially fixed position within the carcass mouth, consisting of a plurality of divergent spring arms disposed entirely exteriorly of the member and having the inner ends thereof connected together adjacent to the tip portion of said member and their outer ends connected to different portions of the margin of the member and adapted to engage yieldingly different portions of the interior of the mouth of the carcass.

11. A device for protecting the tongue of a carcass against mutilation, comprising a cup-shaped member adapted to envelop the tongue and formed of such flexible material that it is readily collapsible, and means for holding said member in a substantially fixed position within the carcass mouth, consisting of a plurality of divergent spring arms extending in different directions from the tip portion of the member and having their inner ends connected together and to said tip portion and their outer ends connected to the marginal portion of the member and adapted to engage yieldingly different portions of the interior of the mouth of the carcass.

12. A device for protecting the tongue of a carcass against mutilation, comprising a cup-shaped member for enveloping the tongue, and means for holding said member in a substantially

- fixed position within the mouth of the carcass, including a pair of laterally spaced, member straddling, rearwardly divergent spring arms having the inner ends thereof connected together adjacent to the tip portion of the member and their outer ends adapted to be pressed together in connection with insertion of the device into the carcass mouth and upon release thereof to spring apart into engagement with the sides of the mouth of the carcass.
13. A device for protecting the tongue of a hog carcass against mutilation during machine de-hairing of the carcass, comprising a flexible cup-shaped member for enveloping the tongue, and means for holding said member in a substantially fixed position within the carcass mouth, including a pair of laterally spaced, member straddling, rearwardly divergent spring arms having the inner ends thereof connected together and to the tip portion of the member and their outer ends connected to the marginal portions of the sides of the member and adapted to be pressed together in connection with insertion of the device into the carcass mouth and upon release thereof to spring apart into engagement with the sides of said carcass mouth.
14. A device for protecting the tongue of a carcass against mutilation, comprising a pair of U-shaped spring metal strips extending at substantially right angles to one another, and having the bowed central portions thereof crossing one another and riveted together and their outer ends forming arms adapted to be pressed together in connection with insertion of the device into the mouth of the carcass and upon release thereof to spring apart into engagement with different portions of the mouth interior, and clip means applied to the crossed central portions of the strips and serving to hold said strips against relative sidewise displacement.

15. A device for protecting the tongue of a carcass against mutilation, including a pair of U-shaped spring metal strips extending at substantially right angles to one another, and having the bowed central portions thereof crossing one another and riveted together and their outer ends shaped to form tooth-equipped outwardly divergent arms and adapted to be pressed together in connection with insertion of the device into the mouth of the carcass and upon release thereof to spring apart into engagement with different portions of the mouth interior, and a metallic clip mounted on the rivet between the crossed central portions of the strips and provided with pairs of opposed oppositely extending flanges in engagement with the side edges of said central portions of the strips and serving to hold said strips against relative lateral displacement.

16. A device for protecting the tongue of a hog carcass against mutilation during machine de-hairing of the carcass, comprising a cup-shaped canvas member for enveloping the outer end of the tongue, means for holding the member in substantially fixed position within the carcass mouth consisting of a plurality of laterally spaced spring arms extending rearwardly and in a divergent manner from the tip portion of the member and having their inner ends riveted together and to said tip portion and their outer ends connected to different portions of the margin of the member and adapted to spring outwards into engagement with different portions of the interior of the mouth of the carcass, and clip means mounted on the rivet and applied to said inner ends of the arms so as to hold said arms against lateral or sidewise displacement one with respect to the others.

REUBEN J. GUNDERSON.
